RESILIENT COMB-TYPE CLEANING BRUSH WITH STIFF SHORT SURFACE PILES AT AN ANGLE TO THE BRUSH SURFACE

Raymond Kieves, 1507 Inkster Blvd.,
Winnipeg, Ontario, Canada

Filed Mar. 11, 1970, Ser. No. 22,912

Term of patent 14 years

Int. Cl. D4—01

U.S. Cl. D4—12

FIG. 1

FIG. 5a

FIG. 5

FIG. 6

FIG. 2

FIG. 3

FIG. 4

FIG. 7

FIG. 8

FIG. 1 is a perspective view of the brush,
 FIG. 2 is a side view of the design shown in FIG. 1,
 FIG. 3 is a top view of the design shown in FIG. 1,
 FIG. 4 is a bottom view of the design shown in FIG. 1,
 FIG. 5 is a front view along the longitudinal axis of

FIG. 1,

FIG. 5a is a cross-sectional view along lines 5a—5a of FIG. 1,

FIG. 6 is a rear view along the longitudinal axis of FIG. 1,

FIGS. 7 and 8 are perspective views of a different species of the embodiment of FIG. 1.

I claim:

The ornamental design for a resilient comb-type cleaning brush with stiff short surface piles at an angle to the brush surface, as shown and described.
